UNITED STATES PATENT OFFICE.

ROBERT NEWBOLD, OF BROOKLYN, NEW YORK.

CAP AND LINER ASSEMBLING MACHINE.

Application filed July 23, 1926. Serial No. 124,412.

The present invention relates to machines for assembling caps and liners therefor, and aims to provide a novel and improved machine of that kind which is simple in construction and operation.

It is also an object of the invention to provide such a machine having novel features of construction to enhance the efficiency and utility thereof, and which may 10 be adjusted for caps and liners of different diameters.

With the foregoing and other objects in view, which will be apparent as the description proceeds, the invention resides in 15 the construction and arrangement of parts, as hereinafter described and claimed, it being understood that changes can be made within the scope of what is claimed without departing from the spirit of the invention.

20 The invention is illustrated in the accompanying drawings, wherein—

Figure 1 is a plan view of the machine, portions being broken away and shown in section.

25 Fig. 2 is a vertical longitudinal section on the line 2—2 of Fig. 1, portions being shown in elevation.

Figs. 3 and 4 are transverse sections on the respective lines 3—3 and 4—4 of Fig. 30 1, portions being shown in elevation.

Fig. 5 is a plan view of the liner supporting and guiding plates.

The machine comprises a suitable frame, which, as shown, has the table 10, and the 35 caps 11 are fed onto said table from one side to a position below a stack of liners 9. As shown, the caps 11 are fed by gravity down a chute 12 leading from one side over one edge of the table 10 to a forwardly extending cap channel defined by longitudinal 40 guide bars 13 and 14 bearing on the table and extending to the front end thereof. The bar 13 is shorter than the bar 14 to provide an entrance in rear thereof through which 45 the caps move from the chute 12 into the channel, and the bar 14 serves as a stop to limit the movement of a cap when it enters the channel from the chute. The cap rests in an inverted position on the table 10 with- 50 in the channel for movement forwardly in the channel. The caps are usually of sheet metal and have their rims formed with screw-threads or other means for attachment to the jars or other receptacles on 55 which the caps are used, and the machine

may be used for caps of different sizes, as will hereinafter more fully appear.

A liner magazine 15 is supported above the table at a point above the entrance or receiving portion of the channel defined by 60 the bars 13 and 14, so that when a cap moves from the chute into the channel it will be positioned below the liner magazine. Said magazine comprises a horizontal plate 16 having a circular opening 17 slightly larger than the liners 9 for the movement of the liners down through said opening. A vertical rod or post 18 has its lower terminal 65 extending slidably through the plate 16 at the front edge of the opening 17 for the contact of the front edges of the liners. The rod 18 is adjusted vertically by means of a screw 19 threaded within the plate 16 in front of the rod 18 and having its head engaging within a notch 20 in the rod 18, so 70 that by rotating the screw said rod may be adjusted upwardly or downwardly accurately. The lower end of the rod 18 may therefore be positioned to allow only the lowermost liner in the magazine to move 75 forwardly under the rod 18 from the magazine. Opposite side rods or posts 21 forming with the rod 18 the "walls" of the liner magazine, have their lower ends secured to 80 slides 22 movable in oblique slideways or 85 channels 23 in the plate 16, and the side edges of the liners 9 are adapted to contact with the rods 21, whereby the vertical rods 18 and 21 guide the liners 9 for downward movement in the magazine to and through 90 the opening 17. The slides 22 are clamped on the plate 16 by the clamping screws 24, and said slides have slots 25 receiving said screws, in order that when the screws are loosened the slides 22 may be adjusted in- 95 wardly or outwardly to decrease or increase the size of the magazine for liners of different diameters. As shown in Fig. 1, the liner magazine is adjusted for liners of the maximum diameter. By adjusting the slides 22 inwardly the rods 21 are moved inwardly and forwardly slightly so as to accommodate liners of smaller diameters. The stack 100 or column of liners 9 may be readily placed in the magazine 15, and such liners may be 105 of paper, cardboard, cork or other material, and are frequently coated or impregnated with wax or other substance.

A horizontal sheet metal plate 25 rests on the guide bars 13 and 14 and extend 110

under the plate 16 to provide a bottom for the liner magazine, the lowermost liner resting on the plate 25. Said plate 25 is provided in front of the liner magazine with a 5 circular opening 26 through which the liner may move downwardly after being moved forwardly from under the magazine. The plate 25 has a longitudinal slot 27 of narrower width than the diameter of the 10 smallest liner for which the machine is intended, extending rearwardly from the opening 26 to the rear end of said plate 25. The plate 25 is a liner supporting plate, and a liner guiding plate 28 is secured on the plate 15 25, and has an opening or slot 29 extending from its rear end to the forward edge of the opening 26 and of a width equal to the diameter of the opening 26. Thus, the lowermost liner in the magazine resting on the 20 plate 25 is guided forwardly within the slot or opening 29 to the opening 26, and the rod 18 is adjusted to permit the lowermost liner in the magazine to move on the plate 25 under said rod, said rod 18 preventing the 25 second or next upper liner from moving out of the magazine, so that the liners are delivered from the magazine one at a time from the bottom of the stack. The forward end of the slot or opening 29 being closed will also 30 serve as a stop to limit the forward movement of a liner when it reaches the opening 26. The plates 25 and 28 are secured on the bars 13 and 14 by screws 30 extending downwardly through said plates and bars into 35 the table 10, thereby also clamping the bars 13 and 14 on said table.

When the machine is adjusted for caps and liners of a smaller diameter than shown in the drawings, the slides 22 are adjusted as 40 above indicated, and the bars 13 and 14 and plates 25 and 28 are removed and replaced by other bars and plates to accommodate the caps and liners of smaller size. Thus, by removing the screws 30, said bars and 45 plates are readily removed from off the table so as to be substituted quickly and conveniently.

The means for pressing the liners into the caps, includes vertical slide rods 31 at opposite sides of the bars 13 and 14 and opening 26, slideable through upstanding guides 32 having feet fastened by screws or bolts 33 on the table 10, and a transverse yoke 34 is fastened to the upper terminals of the 50 rods 31. A tubular plunger stem 35 is screw-threaded through the yoke 34 in a vertical position, and a lock nut 36 is threaded on said stem and bears against the yoke 34 to maintain the adjustment of said stem. 55 A plunger head 37 is engaged over the lower terminal of the stem 35 to move upwardly and downwardly through the opening 26, and a screw 37' extends through the stem 35 with its lower end threaded into the head 60 65 37 and the head at its upper end bearing on

the upper end of the stem 35, for securing the plunger head to said stem.

The plunger head is reciprocated vertically, and for this purpose a transverse yoke 38 is secured to the lower terminals of the slide rods 31, below the table 7, and is pivotally connected, as at 39, with one arm of a longitudinal lever 40 located below the table and mounted on a transverse fulcrum or rock shaft 41 having its terminals journaled in 70 hangers 42 depending from the table. The rear arm of the lever 40 has a roller 43 mounted thereon and working within a circumferential cam groove 44 in a drum or wheel 45 rotatable around a vertical pin or 75 spindle 46 below the table 10. The spindle 46 is secured in a U-shaped bracket 47 secured to and depending from the table, and said bracket has a bearing 48 at one side to which a drive shaft 49 is journaled. The shaft 49 has a pulley wheel 50 thereon for supplying power to the machine, and a bevel pinion 51 on the inner end of said shaft meshes with the bevel gear teeth 52 with which the lower portion of the wheel 45 is 80 provided, thereby rotating said wheel 45. The groove 44 is of such shape as to oscillate the lever 40 to raise and lower the plunger head 37 at the proper time in relation to the operation of other parts of the machine. 85

A feeding plunger or slide 53 is movable on the table 10 between parallel guide bars 54 secured on said table in rear of the liner magazine, and a depending pivot pin 55 carried by the slide 53 is connected by a connecting rod or pitman 56 with a crank pin 57 on the wheel 45, whereby the rotation of said wheel will reciprocate the slide 53 longitudinally on the table. The table has a longitudinal slot 58 in which the pin 55 100 works, and the slide 53 carries the pushers or feeders for moving the caps and liners forwardly.

The cap pusher or feeder comprises a bar or plate 59 disposed longitudinally on the slide 53 and clamped on said slide by means of a clamping screw 60 threaded in the slide, the feeder 59 having a longitudinal slot 61 receiving said screw, in order that the feeder 59 may be adjusted longitudinally, when said 115 screw is loosened, thereby advancing the cap to the proper position from below the liner magazine, when the slide 53 is moved forwardly. The forward end of the feeder 59 abuts or contacts with the cap 11 which is 120 below the liner magazine, for moving said cap forwardly to a position below the opening 26, and the adjustment of the feeder 59 therefore enables the cap 11 to be moved forwardly to an accurate position below said 125 opening 26. The feeder 59 moves under the plate 25.

The liner feeder or pusher comprises a bar or plate 62 bearing on the cap feeder or bar 59, and a screw 63 is threaded in the 130

feeder 59 to clamp the liner feeder 62 thereon, the feeder 62 having a longitudinal slot 64 receiving the screw 63 in order that the feeder 62 may be adjusted longitudinally to 5 properly advance the lowermost liner from the magazine to the opening 26 when the slide 53 is moved forwardly. The clamping screw 63 is located near the rear end of the feeder 62, and said feeder 62 moves in the 10 slot 27 of the liner supporting plate 25. The liner feeder 62 is adjustable for liners of different thicknesses. Thus, an adjusting screw 65 is threaded in the cap feeder 58 below the liner feeder 62, and said liner 15 feeder rests on said screw, so that by adjusting the screw 65 upwardly the forward terminal of the feeder 62 is sprung upwardly so that the forward end of the feeder 62 will properly engage the rear edge 20 of the lowermost liner in the magazine to move said liner forwardly under the rod 18 to the opening 26. The screw 65 has an upstanding portion 66 of reduced diameter received in a longitudinal slot 66' of the 25 feeder 62, and adapted for the engagement of a screw-driver or other implement for conveniently rotating the screw 65. Thus, the feeder 62 may be adjusted upwardly and downwardly according to the thickness of 30 the liners, so as to feed only the lowermost liner from the liner magazine, and the rod 18 will hold back the liners above.

In order to hold the cap in place below the opening 26 for the proper reception of 35 the liner from above, friction pins 67 are slidable transversely in the bars 13 and 14 at opposite sides of the opening 26 and their inner terminals are V-shaped, as at 68, and project slightly from the inner sides of the 40 bars 13 and 14, so that the cap below the opening 26 is maintained in position between the two pins 67 at opposite sides. The outer ends of the pins 67 have flanges 69 within recesses 70 in the outer sides of the bars 13 45 and 14, and said flanges have flat surfaces bearing on the table 10, as seen in Fig. 4, to prevent the pins 67 from rotating, so that their faces 68 are maintained in proper position. Coiled springs 71 are confined between said pins and cover plates 72 secured 50 removably to the outer sides of the bars 13 and 14 across the recesses 70, thereby yieldingly projecting the inner ends of the pins from said bars. The pins preferably have 55 recesses receiving the springs 71, as seen in Fig. 1, and the pins 67 may yield when a cap is forcibly moved forwardly in the channel past said pins.

The plate 16 of the liner magazine is 60 held by the rear bolts or screws 33, thereby supporting the liner magazine above the plate 25.

In operation, the cam groove 44 is so arranged with reference to the crank pin 57, 65 that when the cap and liner feeders are

moved forwardly, the plunger head 37 is raised or retracted, and when the feeders are retracted or moved rearwardly, the plunger head is moved downwardly. Starting with the parts in the position as shown in the drawings, with the wheel 45 rotating in the direction of the arrow as seen in Fig. 3, as the crank pin 57 starts to move forwardly, the lever 40 is swung so as to raise the push rods 31 and depending stem 35 of the plunger head 37, thereby retracting said plunger head upwardly above the opening 26. The feeders 59 and 62 being moved forwardly will result in the forward end of the feeder 59 contacting with the cap 11 70 below the liner magazine, while the forward end of the feeder 62 contacts with the lowermost liner in the magazine. Said cap is therefore slid forwardly on the table 10 below the plate 25 to a position below the opening 26, while the liner is slid on the plate 25 into said opening, to drop downwardly through the opening into the cap. When the cap is moved forwardly to position below the opening 26, it moves past the rear friction pins 67, which are forced outwardly against their spring 71, and said pins then spring inwardly to hold the cap in place under said opening 26. The front pins 67 prevent the cap, when shoved forwardly by the feeder 59, from moving too far or beyond the opening 26. The cap which was under the opening 26 is ejected forwardly by the cap which is moved from below the liner magazine by the feeder 59, the first cap being advanced by the second cap, and being shoved past the front pins 67, while the second cap is shoved by the feeder 59 past the rear pins 67 to a position below the opening 26. Thus, as each cap is moved from below the liner magazine to a position below the opening 26, the previous cap with the liner therein is ejected from the forward end of the channel between the bars 13 and 14. 85

When the wheel 45 turns so as to retract the slide 53 and feeders 59 and 62, the lever 40 is swung by the wheel 45 to depress the plunger head 37, and said plunger head moves downwardly through the opening 26 into the cap below said opening, to force the liner into the cap, as seen in Figs. 2 and 4. When the feeders 59 and 62 have been completely retracted, as seen in Fig. 2, a cap 11 slides in front of the feeder 59 below the liner magazine, and the stack of liners 9 in the magazine moves down on the plate 25, and the operation is repeated for each revolution of the wheel 45. 100

Having thus described the invention, what is claimed as new is:—

1. A machine of the character described comprising a liner magazine, means for supplying caps to a position below said magazine, reciprocatory means for feeding a liner 115

- from under the magazine to a position to drop downwardly and simultaneously moving a cap from under the magazine to a position to receive the liner when dropped, and 5 means for pressing said liner into said cap.
2. A machine of the character described comprising a liner magazine, means for supplying caps to a position below said magazine, reciprocatory feeders for moving a 10 liner from under the magazine to a position to drop downwardly and simultaneously moving a cap from under the magazine to a position to receive the liner when dropped, a plunger for pressing said liner into said 15 cap, and actuating means for operating said feeder and plunger.
3. A machine of the character described comprising a table, a plate thereover, a liner magazine above said plate, means for supplying caps to a position on the table below 20 said plate and magazine, reciprocatory means for moving a liner from the magazine on said plate to a position to drop downwardly and simultaneously moving a cap 25 from below the magazine to a position to receive said liner, and means for pressing said liner downwardly into said cap.
4. A machine of the character described comprising a table, a plate thereover, a liner 30 magazine above said plate, the plate having an opening beyond the magazine for the downward passage of a liner, means for supplying caps to a position on the table below the magazine, reciprocatory means for moving a liner from the magazine to said opening and simultaneously moving a cap from below the magazine to a position under said opening, and means for pressing said liner downwardly through said opening into said 40 cap.
5. A machine of the character described comprising a table, a plate thereover, a liner magazine above said plate, the plate having an opening beyond the magazine for the 45 downward passage of a liner, means for supplying caps to a position on the table below the magazine, a reciprocatory feeder movable on the table for moving a cap from below the magazine to a position under said opening, a reciprocatory feeder movable with the aforesaid feeder for moving the lowermost liner from the magazine to said opening, a plunger movable downwardly through said opening for pressing said liner into said cap, and actuating means for operating said feeders and plunger.
6. A machine of the character described comprising a table having a cap channel thereon, a plate over said channel, a liner 60 magazine above said plate, the plate having an opening beyond the magazine and over said channel for the downward passage of a liner, means for supplying caps from one side into said channel to a position below the magazine, a reciprocatory feeder mov- 65
- able on the table for moving a cap from below the magazine in the channel to a position below said opening, a reciprocatory feeder movable with said feeder for moving the lowermost liner from said magazine to 70 said opening, slide rods movable through the table at opposite sides of said channel, a yoke connecting said rods above said opening, a depending plunger carried by said yoke to move through said opening for pressing the liner through said opening into the cap, and actuating means below the table connected to the first named feeder and said rods.
7. A machine of the character described 80 comprising a liner magazine, means for supplying caps to a position below said magazine, reciprocatory means for feeding a liner from the magazine and simultaneously moving a cap therewith from under the magazine, means for pressing said liner into said cap, and yieldable means for holding the cap in place in the position to receive the liner.
8. A machine of the character described 85 comprising a liner magazine, a cap channel leading from under said magazine, a plate over said channel to support the lowermost liner in said magazine and having an opening beyond the magazine for the movement of a liner down into the channel, reciprocatory means for feeding the lowermost liner in the magazine to said opening and simultaneously moving a cap from below the magazine in said channel to a position below said opening, means for pressing said liner down through said opening into the cap, and yieldable elements at opposite sides of said channel for holding the cap in position below said opening.
9. A machine of the character described, 105 comprising a liner magazine, means for supplying caps to a position below said magazine, a reciprocatory member, and cap and liner feeders movable with said member and adjustable relatively to one another and to said member, the cap feeder being arranged to move a cap from under said magazine and the liner feeder being arranged to move the lowermost liner from the magazine simultaneously.
10. A machine of the character described 110 comprising a liner magazine, means for supplying caps to a position below said magazine, a reciprocatory slide, a cap feeder mounted adjustably on said slide and arranged to move a cap from below the magazine, and a liner feeder mounted adjustably on the cap feeder and arranged to move the lowermost liner from the magazine to a position to drop into said cap.
11. A machine of the character described 120 comprising a liner magazine, means for supplying caps to a position below said magazine, a reciprocatory slide, a cap feeder mounted adjustably on said slide for moving 125

a cap from below said magazine, a liner feeder adjustably secured on the cap feeder for moving the lowermost liner from said magazine simultaneously with the movement 5 of said cap, and means for adjusting the liner feeder upwardly and downwardly relatively to the cap feeder.

12. A machine of the character described, a magazine for a stack of articles, a reciprocatory member, a resilient feeder on said member to move under said magazine for moving the lowermost article therefrom, a

clamping element carried by said member for clamping said feeder thereon, and an adjusting screw mounted in said member under 15 said feeder for springing said feeder upwardly, said screw having an upper reduced portion, and said feeder having slots accommodating said clamping element and reduced portion. 20

In testimony whereof I hereunto affix my signature.

ROBERT NEWBOLD.
